COLLISION-PROOF PAPER OR FIBER WALLED CONTAINER

Jerome J. Galbierz, Glendale, and Peter J. Ditto, St. Ann, Mo., assignors to R.C. Can Company, Overland, Mo., a corporation of Missouri

Filed May 27, 1963, Ser. No. 283,161

3 Claims. (Cl. 229—5.6)

This invention relates to containers with a tubular body and end closures secured to the body by a protruding rolled seam, and more specifically to containers with paper, or fiber, tubular bodies provided with metal end closures seamed thereto which will prevent material damage to the walls of the body due to a collision with the rolled seam of an adjacent container in a shipping carton.

The invention has general utility for containers of the can type and especially for the larger sizes. The invention finds particular utility in cans of the larger sizes used for packaging fluids, for example, containers of the quart size, or larger, used in packaging motor oil.

Taking the oil can example as illustrative of the problem, quart size cans with metal foil lined fiber walls and sheet metal ends are now in common usage for the purpose. Oil is a relatively heavy substance, and, because it is a fluid, it lends no support to the can structure. The packagers deliver the cans in shipping cartons which vary in size and shape but are similar in one respect, that is, a plurality of cans are placed side by side in a rectangular corrugated fiberboard box of the proper size to confine a certain number of rows with a given number of cans in each row. Fiber walled cans of the fluid described are strong enough to resist damage when subject to expected rough handling, when shipped in this manner. However, instances have occurred when the fiber walls have been damaged during shipping, and this damage was so apparent as to cause the consignee to be concerned. In these instances, the fiber wall was damaged immediately adjacent the rolled bead on the can end.

There is a readily explainable reason for this, and the identical damage is easily duplicated by dropping a shipping carton ten or twelve feet onto a concrete floor so that the carton will strike on one end, or one side. When the cans of oil are removed from the carton after such a test, it becomes very evident that the bead on one can, slid off the bead on the next, and dented in the fiber wall. The dent itself is not particularly serious, but, in some instances, the collision of the bead with the fiber wall pulls the wall partly out of the bead on the can end in which it is secured. Thus, it is reasoned that if the weight of the contents, together with the length of free fall is great enough, some of the can walls might be dented so severely as to produce a leak at the rolled seam between the can wall, or body, and the can end closure.

This invention has, as its primary object, to make the fiber walled containers collision-proof especially in this respect.

According to this invention, each end of a fiber bodied can is provided with a novel form of end closure which, when applied to the can, provides an outer circumferential bead of the same rolled form as is usual, but, in addition, provides an inner bead adjacent, or in contact with, the inner wall of the can body above the outer bead (between outer beads). The inner bead is formed by crimping the metal of the can end so that a reinforcement is provided internally of the can body which has a radial resistance to crushing comparable with the outer bead. This construction minimizes the damage due to collision of the outer bead of one can with the wall of the body of the next at the adjacent outer bead of the next.

Other objects and advantages of this invention will appear from the following detailed description which

is in such full, clear and concise terms as will enable any person skilled in the art to make and use the same when taken with the accompanying drawings forming a part thereof, and in which:

5 FIG. 1 is a schematic illustration in top plan of a plurality of cans in a packing case, or shipping carton;

FIG. 2 is a schematic illustration in side elevation of FIG. 1;

10 FIG. 3 is a schematic illustration in side elevation showing the shift in position of the cans under a typical impact situation when a packing case, or carton, is dropped;

FIG. 4 is a fragmentary view in section of action which takes place during a typical collision between cans;

15 FIG. 5 is a sectional view on an enlarged scale illustrating a collision-proof type of can end; and

FIG. 6 is a fragmentary view in section illustrating the action which takes place during a collision between cans provided with collision-proof can ends.

20 This invention will be described as applied to cans which have a multi-ply body formed by spirally winding a paper outer ply over spirally wound plies of paper and metal foil to form a foil lined can body with a label. Metal can ends are applied to opposite open ends of this body by a process which seams the edges of the multi-ply body to the can ends by simultaneously rolling an edge of the body into a bead at the edge of a can end as this bead is formed. After one can end is applied in this manner, the can is filled and the opposite can end applied in the same way. The filled cans are then packed in a shipping case, usually of corrugated fiberboard, or the like, for delivery.

FIGS. 1 and 2 show a shipping case, or carton, 10 packed with a dozen cans, indicated as 11-22, ready for shipping. The carton 10 does not use dividers between rows of cans because of extra cost. Consequently, cans 11-22, when packed, are in contact one with another at the beads in the can ends top and bottom of each can. As will be apparent, some cans will be in contact at two points spaced ninety degrees apart on the beads of the can ends top and bottom, others at three points, and still others at four points top and bottom.

45 Rough handling, during shipping of the cartons, is unavoidable and it often occurs that cartons fall from a stack several feet high. Should the case hit the floor on an end, a corner, or a side, instead of flat on its top or bottom, then the action which takes place is illustrated in FIG. 3. The bead on one can end rides over the bead on the next at the point of contact, and the beads collide 50 violently with the body of the next adjacent can at a location on the body beside a bead. In FIG. 3, cans 19, 20, 21 and 22 are shown during this action to illustrate what might be termed a typical collision between cans due to impact.

55 The damage which can result from collision is shown on an enlarged scale in FIG. 4, especially is this possible if the cans contain a heavy liquid such as a motor oil. At impact, the bead 30 on the metal can end 29 of can 20 rides up the bead 33 of the metal can end 28 on the can 19, and, if the force of the collision is great enough, the bead 30 dents the body 34 of the can 19 as at 35. Should the impact of the case be great enough, it is entirely possible for the collision between cans 19 and 20 to actually cause the edge 36 of body 34 to be partially pulled away from the bead 33. If this occurs, there is a good possibility of oil leakage from can 19 due to collision damage. One possible manner of preventing collision damage of this kind would be to increase the size of the beads 30 and 33 so that protection is afforded further along the can body from the end. Another obvious way would be to eliminate the beads 30 and 33 by causing them to project endwise to the cans instead of out-

wardly of the can walls. Neither of these solutions is attractive however, for several reasons. Changes, such as this, require extensive changes in machinery, and the present beads, such as 30 and 33 on the cans, are looked upon with favor under most instances because they supply strong added protection and reinforcement. When the cans are handled individually, they can be rolled on these beads, rather than on the labels, which would damage, or mar, the printing. When stacked, the beads space the can bodies and provide protection.

This invention provides a solution without a change in assembling machines, or the elimination of the outwardly protruding bead on the can end, which bead functions normally to protect the outside of the body. One example of this invention is illustrated in FIGS. 5 and 6. End closure 50 is crimped circumferentially at 40 to form a first bead, and crimped circumferentially at 42 to form a second bead or shoulder to reinforce the first. Lip 41 is rolled onto the edge of a can body at 51 and 52 in the same way and by the same machinery as the can ends shown in FIG. 4.

Some of the advantages accruing from this change in can ends is illustrated in FIG. 6. Here two cans 19 and 20' are shown during a typical collision between cans in a shipping carton. Each can is provided with a can end 50. When secured to the cans 19' and 20', the can ends 50 are formed with a beaded edge, such as 51, on can 19', and 52, on can 20'. Both beads are the same, and both are the same as the beads 30 and 33 because the same machine has been used to apply the can ends 50 as was used to apply the can ends 28 and 29. As the impact takes place, the effect is illustrated in FIG. 6 by the action of the bead 52 which rides over bead 51 and strikes the fiber wall 34' of the can 19'. The construction of can end 50 is such that internal bead 40 is positioned internally of the can wall 34' approximately in the location of the zone of impact between the bead 52 on can 20' and the wall 34' of the can body 19'. Because of this reinforcement bead 40, wall 34', instead of absorbing the force of the collision alone, now becomes merely a paper cushion between bead 52 and bead 40. Not only is the wall 34' protected from damage, but it becomes a shock absorber to cushion the impact of the collision.

This construction of can end closure produces an entirely different product which is not only collision-proof in the sense that leakage becomes an extremely remote possibility due to collision between cans, but also in the sense that visible damage from collision between cans is avoided. This visible damage is sometimes more important because it often creates more complaints than actual destruction of one or more of the cans in the shipping carton.

Bead 42 provides added strength to the first bead 40 by stiffening each edge of the cylindrical ring of metal formed in the end closure 50 between circumferential crimps 40 and 42. This stiffening ring distributes the force of a collision at one point and avoids concentration of forces. It will be appreciated that when both ends of a can are equipped with this type of end closure 50, damage is avoided at either end.

Changes in and modifications of the construction described may be made without departing from the spirit of our invention or sacrificing its advantages.

Having thus described the invention, what is claimed and desired to be secured by Letters Patent is:

1. In a can having a tubular body, can ends on said tubular body, and a circumferential rolled seam between the edges of said can ends and the edges of said can body forming a protective bead at each end of the can body protruding outwardly of the can end around the sides of the body, the improvement for eliminating damage to one can body from the beads on an adjacent can located side by side when can tilting during a collision between cans in a shipping carton is caused by an impact on the shipping carton, comprising,

25 (a) a second circumferential bead with a radial resistance to crushing comparable with said rolled seam located on one of said can ends spaced inwardly of one of said protective beads and extending toward and along the inside of the can body within the can from said protective bead toward the opposite can end to back up the can body in a circumferential zone within a width less than a bead width of said protective bead when the beads on adjacent side by side cans slip out of protective contact with one another by tilting which displaces the cans relatively axially during a collision.

2. The combination as defined in claim 1 in which the can is a tubular fiber body, the can ends are of metal.

3. The structure defined in claim 1 and said second circumferential bead forming an annular offset shoulder around the inside of each can end, the width of said shoulder being sufficient to provide the reinforcement required for forming and for subsequent operation.
